Primary Examiner — Manpreet Matharu*Assistant Examiner* — Mojtaba Tehrani(74) *Attorney, Agent, or Firm* — Harness, Dickey & Pierce, P.L.C.(57) **CLAIM**

The ornamental design for an antenna housing, as shown and described.

DESCRIPTION

FIG. 1 is a front right perspective view of an antenna housing, showing my new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken line in the figure drawings represents unclaimed environment only and forms no part of the claimed design.

1 Claim, 6 Drawing Sheets(56)
